UNITED STATES PATENT OFFICE.

FRANK KERN, OF MATTOON, ILLINOIS.

DESIGN FOR A STOCKING-SUPPORTER.

SPECIFICATION forming part of Design No. 26,614, dated February 9, 1897.

Application filed June 1, 1896. Serial No. 593,928. Term of patent 14 years.

To all whom it may concern:

Be it known that I, FRANK KERN, a citizen of the United States, residing at Mattoon, in the county of Coles and State of Illinois, have 5 invented and produced a new and original Design for Stocking-Supporters, of which the following is a specification, reference being had to the accompanying drawing, showing a part thereof.

- o My design relates to stocking-supporters. The drawing represents a perspective view of my design.
- A represents curved shoulder-straps leading from the waist upwardly over the shoulders. At the point B, where they go over the top of the shoulders, the straps A are made wider than at the lower ends by being gradually narrowed in from the top toward the bottom. The straps A themselves curve 5 outwardly from about the middle portion toward the lower ends. These shoulder-straps are united in front and rear across the breast portion by cords or X-shaped bands or straps

D D, which pass each other substantially at mid-length and are secured to each other and 25 at their opposite ends.

E F are Y-shaped bands, the upper diverging ends being secured to the shoulder-straps and the lower end F permitting the attachment of adjustable stocking-supporters. 30

The whole garment and supporter forms a pleasing and distinctive design or shape which is clearly distinguishable in its character from any goods which are now on the market. 35

Having described my invention, what I claim is—

The design for a stocking-supporter, substantially as shown and described.

In testimony whereof I herewith subscribe 40 my name this 26th day of May, 1896.

FRANK KERN.
